SCREW DRIVER

Charles S. Schaffer, Chicago, Ill.

Application July 24, 1936, Serial No. 92,352

4 Claims. (Cl. 145—50)

This invention relates to an improvement in screw drivers and has as a principal object the provision of a screw driver which will itself hold a screw while the same is being inserted.

5 A further object of the invention is the provision of a screw holding screw driver which is positive in action and which may be operated with one hand, the mechanism being controlled by a simple movement of the thumb or finger.

10 Another important object of this invention is to provide a screw driver which may readily be used for rough work without danger of damage to the screw holding elements, which, as shown on the drawings and set out in this specification, 15 may be withdrawn into the mechanism, when the screw driver is used in any manner other than as a screw holding tool.

A further object of this invention is to provide a screw driver as above set out which is of simple 20 and sturdy construction and free from a multiplicity of parts.

A further highly important object of this invention is to provide a screw driver of the screw-holding type which is easy and economical to 25 manufacture.

Other and further objects will be apparent from drawings and the detailed description in this specification.

On the drawings:

30 Fig. 1 is a view of the invention in elevation.

Fig. 2 is a view partially in elevation, the remainder in section, giving a principally central vertical sectional view of the internal mechanism.

35 Fig. 3 is a sectional view of the hollow mechanism-containing cylinder and the solid operating cylinder and operating button taken on the line 3—3 of Fig. 1, the operating button being in elevation.

40 Fig. 4 is a central vertical sectional view of the mechanism-containing cylinder.

Fig. 5 is a central vertical sectional view of the wedge-shaped end bit or blade of the screw driver, showing the longitudinal center hole 45 through the same.

Fig. 6 is an elevational view of the internal mechanism of the screw driver showing the solid cylinder, operating button, or headed screw, coil spring and wire screw-kerf gripping rod shaft or 50 bit.

Fig. 7 is a perspective view of the screw driver tip engaging a conventional screw head.

Fig. 8 is a diagram taken on the line 8—8 of 55 Fig. 3, showing the point of the screw driver in its position relative to the kerf or slot in a screw

head when the kerf-gripping rod is retracted or rotated parallel to the blade.

Fig. 9 is a diagram taken on the same line as Fig. 8, illustrating the action of the wedge-shaped end of the rod as it engages the side walls of the 5 slot in a conventional screw head.

Fig. 10 illustrates a modification of the invention for use with standard bit-retaining clamps or jaws such as are used on drills, braces and the like.

10 As shown on the drawings:

The numeral 11 illustrates a handle such as is conventionally used on screw drivers and other hand operated tools. At its upper end the handle 11 carries the sleeve member 12, the rearmost section of which may extend substantially into the center of the handle or may extend therethrough or may be held by other mechanical means. As shown in Fig. 2, this sleeve is tapered at its upper end and centrally bored a portion of its length to receive and retain the hollow mechanism-enclosing cylinder 13.

20 Cylinder 13 extends into and is butt-welded or fastened by a transversely extending pin to the sleeve member 12 at its rearmost portion, as shown in Fig. 2. Enclosed within cylinder 13 is the spring-retained slideable and partially rotatable solid cylinder member 15. At its lowermost end solid cylinder member 15 is reduced in size, a shoulder extending around its entire circumference, the reduced portion 15b extending substantially into the center space between the coils of spring 17.

25 A substantially L-shaped guide slot 13a is cut through the side walls of cylinder 13, the shorter portion of said slot extending longitudinally of said cylinder and the longer part extending laterally of the cylinder. Extending through the L-shaped slot is the mechanism operating button or headed screw 16 comprising a head 16a and a threaded shank 16b which may be threaded into the hole 15a in member 15, as shown in Fig. 3.

30 A metal coil spring 17 of desired length and elasticity is spot welded or otherwise fastened to cylinder member 15 and extends longitudinally in hollow member 13. It is also preferably spot welded or otherwise fastened, as indicated in Fig. 2, at its extreme end in the relative position hereinafter described, to the inner wall of said cylinder member or may be attached, for example, to the rearward end of tip member 14.

35 The tip member 14 is a metal cylinder. In preferred form it may be tapered out as shown on the drawings, but it may also be a cylinder of 40

uniform thickness throughout. At its rearward end it is offset and formed into a shoulder so that it may be inserted into and retained in the end of cylinder 13, forming a smooth union of these parts. A longitudinal hole 14b is chambered or bored the entire length of tip 14 to accommodate and rotatably and slidably retain the rod shaft or bit 18. At its extreme end, the tip member 14 is wedge-shaped, as is the usual construction in screw drivers, forming an end substantially perpendicular to the long axis of the screw driver.

The rod 18 passes through the center of spring 17 and extends into and is fixedly attached to cylinder member 15. As shown in Figs. 1, 2, 7 and 10, the center of the screw contacting wedge portion of tip 14 is cut away at its intermediate portion to accommodate the wedge-shaped end 18a of rod 18. End 18a is wedge-shaped, being as wide in its most narrow direction as the extreme end of tip 14a, and being no wider in its widest portion than the diameter of hole 14b, to allow retraction of rod 18 into hole 14b.

As shown in Fig. 8, in inoperative position the wedge-shaped end of said rod remains parallel to the wedge-shaped portion of the top of the screw driver blade. As shown in Fig. 9, in operative position this wedge-shaped end 18a is rotated so that the corners formed by the opposed surfaces engage and impinge upon the adjacent inner surfaces of a conventional screw slot. To assemble this tool, the rod shaft or bit 18 is inserted into and spot welded to cylinder member 15. The coiled spring 17 is likewise spot welded to cylinder member 15, as shown in Fig. 6. This assembly is then inserted into cylinder 13, the threaded hole 15a in cylinder member 15 being positioned beneath the cut-out L-shaped slot 13a in said cylinder. The operating button 16 is then inserted through the L-shaped slot and the shank 16b is then securely threaded into the hole 15a in cylinder member 15. The coil spring 17 is then compressed in cylinder 13 and rotated so as to put tension on the now relatively fixedly retained cylinder member 15, creating a tendency in rod 18 to both project and rotate.

While in this position, the loose end of spring 17 is fastened, preferably by spot welding to the inner surface of cylinder 13 or to the rearward end of tip 14 so that the spring has a normal tendency to rotate the rod 18 in a counterclockwise direction, looking at the handle butt end. This assembly is then inserted into sleeve member 12 and tip member 14 is then slipped over the rod 18 and placed in contact, as illustrated in Fig. 2, with the upper end of cylinder 13.

Cylinder 13 is then butt-welded to tip member 14, and fastened by means of a pin to sleeve 12. After the welding operations are completed, the handle 11 may be attached. However, in the modified structure shown in Fig. 10 it is obvious that no handle need be attached inasmuch as the rearmost end is designed to be inserted in a conventional drill chuck.

When the screw driver is used as a conventional tool the operating button 16 is positioned in the rearmost section of the substantially L-shaped slot 13a, where it is retained by the tension of the rotated spring 17, causing friction between the shank 16b and the edges of the L-shaped slot. While thus held, the wedge-shaped end of rod 18 is substantially parallel to the extreme outer edge of the tip 14a, although then retracted in hole 14b.

When used as a screw holding screw driver the

operating button 16 is slipped forward, the action of spring 17 forcing cylinder 15 and attached rod 18 to slide forward into the slot and tip 14a and rotate. In most extended and rotated position the wedge-shaped end 18a of rod 18 is substantially perpendicular to the contacting edge of tip 14a.

It is apparent from the foregoing description and attached drawings that I have invented a screw driver which has all the advantages herein set out and accomplishes these objects by novel mechanical means.

I am aware that numerous details of the construction of my invention may be varied through a wide range without departing from the principles of my invention, and I therefore do not desire to limit my patent to the particular or preferred form illustrated.

I claim:

1. In a screw driver adapted to hold a screw while being inserted, the combination of an end adapted to be gripped, a hollow cylinder forming a casing and having a substantially L-shaped slot in the side thereof, the topmost portion of said slot extending rearwardly parallel to the axis of said hollow cylinder and forming a recess extending rearwardly, a manually operable lever extending through said slot and fastened to a plug in said cylinder and rotatable and retractable in said cylinder within the limits defined by said L-shaped slot, a coil spring in said cylinder fastened at one end to said plug forwardly thereof and at the other end to the internal surface of said cylinder imparting resilient movement to said plug, an end portion attached to said cylinder having a wedge-shaped bit forming a main bit adapted to contact a screw kerf and having a longitudinal central bore therethrough and a secondary bit in said bore extending longitudinally therein axially through said spring in said cylinder and fastened to said plug in said cylinder and rotatable and retractable therein in conjunction with the like movement of the spring controlled plug and the manually operable lever said secondary bit being coterminous with the end of said main bit in most extended position and retracted therein when the manually operable lever is placed in the rearwardmost portion of said L-shaped slot.

2. A screw driver comprising a handle, a sleeve connected thereto and extending therein, a tubular cylinder fastened to said sleeve and handle having a substantially L-shaped slot therein adapted to allow an external manually operable lever to extend therethrough, the rearwardmost portion of said L-shaped slot forming a recess parallel to the longitudinal axis of said tubular cylinder adapted to removably lock said lever in relatively retracted position, a solid cylinder in said tubular cylinder fastened to said lever, a coil spring positioned longitudinally in said tubular cylinder forwardly of said solid cylinder and fastened rearwardly on the frontmost portion of said solid cylinder and at its forward end to the internal wall of said cylinder creating a tension, a retractable bit extending longitudinally within the coils of said spring in said tubular cylinder and attached to said solid cylinder, and an end member having a bifurcated wedge-shaped tip and a longitudinal central bore, said retractable bit adapted to be rotated and retracted in said bore in cooperation with said solid cylinder and said lever attached thereto and in most extended position coterminous with said tip and adapted to turn angularly thereto and grip the kerf of 75

screw and removably retain the same on said wedge-shaped tip.

3. In an article of the described class the combination of a centrally longitudinally bifurcated truncated tip forming a main blade adapted to be inserted in the kerf of a screw and having a longitudinal central bore therethrough, said tip rigidly attached rearwardly to a hollow barrel having a substantially L-shaped slot formed in the wall thereof, the said L-shaped slot extending rearwardly parallel to the longitudinal axis of said barrel at its rearwardmost part and in a plane at right angles to the longitudinal axis of said barrel at its end nearest the tip of said blade, a movable spring retained cylindrical plug in said barrel, a lever attached to said plug and extending outwardly through said L-shaped slot and permitting movement of said plug within the limits of said slot, a secondary blade having a truncated tip rigidly attached to said plug and extending forwardly thereof centrally in said barrel and in the central longitudinal bore of said main blade and being coterminous with the tip of said main blade in most extended position and retracted in said main blade in most retracted position, a coil spring in said hollow barrel mounted forwardly of said plug and extending longitudinally in said barrel adapted to create a tension on said plug in any position of said plug with respect to said L-shaped slot, and means adapted to permit gripping of the entire device.

4. In a screw driver the combination of a main blade having a bifurcated wedge-shaped tip and having a longitudinally extending central bore extending therethrough, a semi-rotatable and retractable secondary blade having a truncated tip mounted in said central bore in said main blade,

a hollow tubular cylinder rigidly attached rearwardly of said main blade, said tubular cylinder being provided with a substantially L-shaped slot in the wall thereof, the rearwardmost portion of said slot extending rearwardly of said tubular cylinder parallel to the longitudinal axis thereof forming a rearwardly extending recess, a coil spring extending longitudinally in said tubular cylinder, the rearwardmost end of said spring being rigidly attached to a semi-rotatable and relatively retractable cylindrical plug and the forwardmost end of said spring being attached to the inner wall of said tubular cylinder, a semi-rotatable and retractable cylindrical plug forming a rearward mounting for said secondary bit, 15 an operating lever extending through the L-shaped slot in said tubular cylinder and rigidly attached to the cylindrical plug in said tubular cylinder adapted to permit spring retained and restricted movement of said cylindrical plug and 20 the secondary bit attached thereto within the space limited by the movement of said lever in said slot, said secondary bit being retracted from the bifurcated wedge-shaped tip of said main blade when said operating lever is in the rearwardmost portion of said L-shaped slot and coterminous with the tip of said main blade and semi-rotatable substantially crosswise with respect thereto when in most extended position, the wedge-shaped tip of said secondary blade 25 thereby gripping the edges of the kerf of a screw and releasably retaining said screw on the tip of said main blade, and an end extending rearwardly of said hollow tubular cylinder forming a means for holding the device above described.

CHARLES S. SCHAFFER.
